UNITED STATES PATENT OFFICE

PAUL LITTY, OF LEIPZIG, GERMANY

DRAWING MECHANISMS IN TEXTILE MACHINES

Application filed November 18, 1931, Serial No. 575,928, and in Germany November 25, 1930.

It has already been proposed to ascertain the distance of the feed rollers from the drawing rollers in textile machines by means of a weight-loaded feeler adapted to be mounted on a band of fibrous material. For arriving at the weight in each case it is necessary to know the yarn number or count, or, more correctly, the count as already changed by the drawing rollers.

10 The invention provides means whereby this can be ascertained more rapidly and accurately and also independently of the count.

A device for carrying out the method is illustrated in the accompanying drawings by 15 way of example in which

Fig. 1 is a plan view of the device (the upper pair of feed rollers being removed),

Fig. 2 a front view of the device,

Fig. 3 a side view of the same partly in 20 section, for showing the means for driving the pairs of feed rollers (section on line III-III of Fig. 1),

Fig. 4 a section of Fig. 1 on line IV-IV,

Fig. 5 a side view partly in section through 25 various parts of the driving means for the pairs of feed rollers (section on line V-V of Fig. 1),

Fig. 6 a side view of the band of fibrous material to an enlarged scale, when the nipping point of one pair of feed rollers is displaced (wavy),

Fig. 7 a side view of the same after a pair 30 of feed rollers has been displaced and the correct distance of the pair of feed rollers has been ascertained (stretched straight again).

In the drawings $a_1, a_2, b_1, b_2, c_1, c_2, d_1, d_2$ are pairs of feed rollers of the ascertaining device which correspond to the feed 40 rollers of the drawing mechanism of a textile machine. These feed rollers will be herein-after referred to throughout as "rollers". At e the driving means of a pair of rollers, namely of a_1, a_2 is indicated by a crank. This 45 drive can of course also be effected by me-

chanical means from a countershaft or by a driving machine, for instance an electric motor. The top rollers a_2 to d_2 are loaded in a known manner by weights f attached to pull members. The pairs of rollers are journaled in housings g, h, i, k . The housings g are made integral with the bedplate l and the housings h are integral with a plate m which is slidable on the said bed plate and which itself forms a guide for the displacement of the housings i and k . The displacement of the housings of the pairs of rollers is effected by conveyor spindles n with three separate threaded parts n_1, n_2, n_3 , the threads of which are differently handed and of different pitch. o is a guiding roller in front of the pairs of rollers. At p and q are indicated two bands of fibrous material, for instance rovings, which travel through the device. For the foremost draw the pairs of rollers a_1, a_2 to b_1, b_2 form the nipping points.

According to the invention by altering the distance between the nipping points of the pairs of feed rollers, for instance by moving the nipping points of a rear pair of feed rollers forward towards that of the pair of feed rollers disposed in front of it an artificial waving of the band of fibrous material is produced when it leaves the forward pair of feed rollers and this waving is caused to disappear again by altering the distance between the pairs of feed rollers.

For this displacement of the nipping point 80 a push or pull member is used. In the constructional example shown in the drawings a push member is selected which consists of a knife edge 2 mounted slightly in front of the pair of rollers b_1, b_2 on a lever 1. The lever is pivoted at 3, is provided with a handle 4 and is balanced by a weight 5. On the handle an adjusting screw 6 is provided which on coming in contact with a stop 6' limits the 85 rocking motion of the lever 1 and consequently of the lift of the knife edge 2. On 90

the lever 1 being rocked by means of the handle 4 in the direction of the arrow A the band of fibrous material is forced upwards between the pairs of rollers a_1, a_2 and b_1, b_2 , as is indicated by p' . As the lever 1 grips with its knife edge 2 the drawn band of fibrous material between the nipping points (rollers a_1, a_2, b_1, b_2) and bends out of its plane under pressure, a new nipping point 10 is formed on the knife edge 2 and the nipping point hitherto formed by the rollers b_1, b_2 no longer acts to the full extent, but the nipping point of the rollers b_1, b_2 is displaced to the same extent on the knife edge 2. In this case the band of fibrous material commences to become wavy in a vertical plane, as shown in Fig. 6. By removing the pair of rollers b_1, b_2 away from the pair of rollers a_1, a_2 this waviness can again be 15 caused to disappear, so that the band of fibrous material will again be straight, as indicated in Fig. 7. At the moment in which the waviness disappears the correct distance between the nipping points is ascertained 20 and this distance can be read off on a scale 7. The determination of the moment in which the waviness disappears is facilitated if the knife edge 2 be alternately raised through being rocked in the direction of the arrow A. 25 and rocked in the direction of the arrow B. For accurately observing the waviness a mirror 8 with a sighting tube 9 is provided, in which the image of the band of fibrous material as seen from the side appears, as indicated in Fig. 1. The sighting tube is suitably provided with a covering plate 10 which prevents the band of fibrous material being seen from above, which might interfere with the observation from the side. 30 For the displacement of the separate housings h, i, k the following arrangement is provided: 35

In the frame of the device nuts 11 are rotatably mounted, which turned by a worm gear 12, 13 allow of the spindles being displaced in the direction of the arrows D and E without turning the same. The spindles cannot then turn as they are prevented from so doing by the key 11' of the worm wheel 12'. In 40 the housings h a female thread (not shown) for the spindles is provided, in which the threaded part n_1 moves. 14 are adjustable collars which are fixed on the spindle. Between these adjustable collars 14 the spindle 45 has no thread. The adjustable collars act as drivers for the housings i . 15 is a rotatable nut in the housings k , which can be turned by means of a worm gear 16, 17, but acts during the rotation of the spindles only as a female 50 thread in the housings k , as it is then prevented by the worm 17 from taking part in the rotary motion.

For the purpose of increasing the distances 55 between housings to the same extent, the spindles n are turned for instance by means of

a crank 18', the worm gear 13', 12' and the driving key 11'. The housings h are thereby displaced in the direction of the arrow F and the housings k in the direction of the arrow G. The distances $i-h$ and $i-k$ can be increased 70 by the thread n_1 being for instance right-handed, while the thread n_2 is left-handed. The pitch of the two threads must, however, be the same. On the spindle being turned, the threaded part n_3 will also turn in the nut 11 75 which is locked by the worm gear 13, 12 and will thereby displace the spindle n with the housings i in the direction of the arrow G. The thread n_3 has the same handedness as the thread n_1 , but its pitch is twice as great. 80 The effect of this is that on the distance, for instance, of i to g being increased or decreased by two millimetres, the distance of h from i and of k from i will be increased or diminished by one millimetre and that of h from g 85 also by one millimetre.

The arrangement described makes it possible to vary the distances of the separate housings simultaneously by the same amount, that is, if for instance the housings h are 90 moved away from the housings g by one millimetre, the housings i are at the same time removed from the housings h and the housings k from the housings i each by one millimetre. 95

In order to enable the distances between the housings to be varied to any extent, there are provided worm gears 12, 13 and 16, 17. On the nut 11 being turned by means of the worm gear 12, 13, for instance by a crank 18, the spindle can without turning be displaced in the direction of the arrows G or F and with it are moved the housings h, i and k , while retaining their mutual distance apart. Only the distance between g and h is altered since g is immovable and has no connection with the spindle n . 100

In order to enable the distance between k and i to be increased or decreased alone, the nuts 15 are turned by means of the worm gear 17 and 16 and the housings k thereby displaced on the stationary spindles for instance in the direction of the arrow G. The corresponding distance can be read off on a 105 scale 19. 110

When it is desired to alter the distance of the housings i from the housings h alone, this can be effected by turning the cranks 18 and 18' simultaneously, the crank 18' being turned twice as often as the crank 18. Means may also be provided whereby the worm gears of these cranks are interconnected by a shaft in such a manner that on the said shaft being turned for instance by means of bevel wheels, the spindle of the crank 18' performs twice the number of revolutions as the spindle of the crank 18. The distance 115 between the housings i and h can be read off on the scale 20. 120

The operation may of course be carried out 125

in the opposite way, the pairs of rollers being first set too far apart and then gradually approached towards one another until a waviness is just about to commence.

5 In order to enable not only the distance between the pairs of rollers, but also the draught of the band of fibrous material to be adjusted and varied rapidly within wide limits, the drive of these pairs of rollers is also 10 made variable, by for instance interposing step wheel gear between the separate pairs of rollers. In the example shown in the drawings the drive is transmitted from the driven roller a_1 over a number of intermediate 15 wheels to a shaft 21. On the latter shaft is mounted a toothed wheel 22. On another shaft 23 is fixed a step cone 24. A shaft 25 is journalled in the frame of the device, on which is mounted a toothed wheel 26. On 20 one side a toothed wheel 27, which meshes with the toothed wheel 22, is adapted to be brought into engagement with each step of the step cone 24 and for this purpose is slideable together with the toothed wheel 22 on 25 the shaft 21 and is adapted to be lifted off the step cone by means of a handle 28. A weight 29 keeps the toothed wheel 27 normally in engagement with a corresponding toothed wheel of the step cone 24. On the other side 30 is a similar toothed wheel 30 which meshes with the toothed wheel 26 and which is adapted to engage with the separate steps of the step cone 24. This toothed wheel is also capable of being lifted out of engagement by 35 means of a handle 31, and is normally kept by a weight 32 in engagement with a step of the step cone 24. On the shaft 23 a toothed wheel 33 is keyed which drives the roller d_1 through a rocking gear 34, 35. The rocking gear allows of a displacement of this roller without the wheels of the rocking gear coming out of engagement with one another. On the shaft of the roller d_1 is mounted a further step cone 36 and on the shaft of the 40 roller c_1 a toothed wheel 37 is mounted so as to slide thereon. A toothed wheel 38 which meshes with the said toothed wheel is adapted to be brought into engagement with the separate steps of the step cone 36. This 45 wheel is mounted so as to turn in a hand lever 39 on the shaft of the roller c_1 and in this way transmits the rotary motion of the roller d_1 to the roller c_1 irrespective of the distance of these rollers from one another. At 40 and 50 41 securing arrangements are indicated, by which the position at any time of the toothed wheels 27 and 38 with respect to their associated step cones 24 and 36 can be determined and maintained. Through a similar rocking gear a roller b_1 is driven from the shaft 55 25.

From the above description it will be seen that by displacing the toothed wheels 22 and 27 the ratio of the speed of revolution between the rollers a_1 and d_1 can readily be varied,

by displacing the toothed wheels 37 and 38, the ratio of the speeds of revolution between d_1 and c_1 and by displacing the toothed wheels 26 and 30 the ratio of the speeds of revolution between d_1 and b_1 . 70

The arrangement is such that the third pair of rollers may be given the same speed as the fourth pair of rollers, for changing over from a four roller drawing mechanism to a three roller drawing mechanism. 75

Behind the place where the band of fibrous material leaves the drawing rollers is a matt plate 44 illuminated for instance by sources of light 42, 43, which acts as a sliding surface for the band of fibrous material. 80

The arrangement just described enables the draught between the separate housings to be altered rapidly while the device is in operation, and namely so rapidly that the image of the band of fibrous material which appears on the plate 44 enables the change from one draught to another to be clearly seen and the most suitable draught thus ascertained. The image of the band of fibrous material on the matt plate also enables the effect of 85 the position of the rollers and the loading of the rollers to be seen. 90

What I claim is:

1. A device for ascertaining the correct 95 distance and the most favourable draught of the feed rollers of drawing mechanisms in textile machines, consisting of a plurality of pairs of feed rollers, means for driving the same, means for varying the distance between the pairs of feed rollers, a band of fibrous material running through between the feed rollers and a feeler lever which is capable of being brought into engagement with the band of fibrous material, of displacing the nipping point of the band of fibrous material and of 100 acting on the broad side thereof, as and for the purpose set forth. 105

2. A device for ascertaining the correct distance and the most favourable draught of the feed rollers of drawing mechanisms in textile 110 machines, consisting of a plurality of pairs of feed rollers, means for driving the same, means for varying the distance between the pairs of feed rollers, also when the machine is in operation, a band of fibrous material running through between the feed rollers, a feeler lever which is capable of being brought into engagement with the band of fibrous material, of displacing the nipping point of the band of fibrous material and of 115 acting on the broad side thereof, and a device for observing the narrow side of the band of fibrous material, as and for the purpose set forth. 120

3. A device for ascertaining the correct 125 distance and the most favourable draught of the feed rollers of drawing mechanisms in textile machines, consisting of four pairs of feed rollers, one stationary and three displaceable housings in which the pairs of feed roll-

ers are journaled, means for driving the pairs of feed rollers, longitudinally displaceable spindles for moving the three housings, on each spindle a thread, next to the thread 5 another thread having the same pitch as the first thread but of opposite hand and at the end of the spindle a thread of double the pitch, a band of fibrous material running through between the feed rollers, a feeler 10 lever which is capable of being brought into engagement with the band of fibrous material, of displacing the nipping point of the band of fibrous material and of acting on the broadside thereof, and a device for observing 15 the narrow side of the band of fibrous material, as and for the purpose set forth.

4. A device for ascertaining the correct distance and the most favourable draught of the feed rollers of drawing mechanisms 20 in textile machines, consisting of a plurality of pairs of feed rollers, means for driving one pair of feed rollers, an adjustable step wheel gear between each of the separate pairs of feed rollers for transmitting the drive 25 of the same from the first-named pair of feed rollers and for rapidly varying the draughts between the separate pairs of feed rollers, means for varying the distance between the pairs of feed rollers, a band of 30 fibrous material running through between the feed rollers, a feeler lever which is capable of being brought into engagement with the band of fibrous material, of displacing the nipping point of the band of fibrous 35 material and of acting on the broad side thereof, and a device for observing the narrow side of the band of fibrous material, as and for the purpose set forth.

5. A device for ascertaining the correct 40 distance and the most favourable draught of the feed rollers of drawing mechanisms in textile machines, consisting of a plurality of pairs of feed rollers, means for driving the same, means for varying the distance between the pairs of feed rollers, a band of 45 fibrous material running through between the feed rollers, a feeler lever which is capable of being brought into engagement with the band of fibrous material, of displacing the nipping point of the band of fibrous 50 material and of acting on the broad side thereof and a mirror with a sighting tube for enabling the narrow side of the band of fibrous material to be observed, as and for the purpose set forth.

6. A device for ascertaining the correct 60 distance and the most favourable draught of the feed rollers of drawing mechanisms in textile machines, consisting of a plurality of pairs of feed rollers, means for driving the same, means for varying the distance between the pairs of feed rollers, a band of 65 fibrous material running through between the feed rollers, a feeler lever which is capable of being brought into engagement with

the band of fibrous material, of displacing the nipping point of the band of fibrous material and of acting on the broad side thereof, a mirror with a sighting tube for enabling the narrow side of the band of fibrous material to be observed, a matt plate located at the place where the band of fibrous material leaves the last pair of feed rollers and lamps for illuminating the matt plate with diffused light, as and for the purpose 70 set forth.

In testimony whereof I have signed my name to this specification.

PAUL LITTY.
